UNITED STATES PATENT OFFICE

JOHN H. HICKEY, OF SAN FRANCISCO, CALIFORNIA, ASSIGNOR TO HICKEY FUSE & MANUFACTURING COMPANY, OF SAN FRANCISCO, CALIFORNIA, A CORPORATION OF CALIFORNIA

REFILLABLE ELECTRIC FUSE

Application filed December 19, 1928. Serial No. 327,119.

My invention relates to improvements in refillable electric fuse construction wherein a terminal member of a fuse is detachably clamped into engagement with a plate seated upon the end of a fuse casing to seal said casing against leakage, said plate and the clamping means being removable as a unit to permit the replacing of a fusible element between the terminals of a fuse. 5
10 The present invention is directed to an improved construction and arrangement of the sealing and clamping means as disclosed in my co-pending application, Serial No. 291,039, filed July 7, 1928, and consists of improved details of construction adapted to simplify and facilitate the construction and operation of the device. 15

The primary object of my invention is to provide an improved refillable electric fuse 20 construction.

Another object is to provide an improved means for assembling the fuse which will facilitate the refilling of the fuse.

A further object is to provide an improved 25 construction whereby the clamping means is effectually centered and provided with an adequate bearing upon which said means may be turned to and from clamping position.

Another object is to provide an improved 30 structure wherein the clamping means is held in assembled relation with the sealing plate and provided with means for limiting the movement of the clamping means relative to the plate to facilitate alining and operating the device.

A still further object is to provide an improved construction in which the clamping means and the sealing plate are held in assembled relation and at the same time arranged to be swung apart for inspection and 40 cleaning.

I accomplish these and other objects by means of the improved device disclosed in the drawings forming a part of the present application wherein like characters of reference are used to designate similar parts throughout the specification and drawings, and in which—

Fig. 1 is a longitudinal section of a fuse 50 embodying my improvements;

Fig. 2 is a side elevation, partly in section, of the fuse, the view being taken at right angles to the positions shown in Fig. 1;

Fig. 3 is an elevation of the outer side of the sealing plate; 55

Fig. 4 is an elevation of the outer side of the clamping member;

Fig. 5 is an elevation of the clamping member as mounted upon the sealing plate and indicating the manner in which said clamping member may be turned to an inoperative position; 60

Fig. 6 is an elevation of the inner side of the clamping member;

Fig. 7 is an elevation of the inner side of the sealing plate; 65

Fig. 8 is transverse section of the sealing plate and clamping member assembled in operative relation.

Referring to the drawings, the numeral 1 70 is used to designate in general the casing of a fuse, said fuse being provided with terminal members 2 arranged to receive the ends of a fusible element 3 extending axially between said members 2 within the casing 1. 75 The terminal members 2 are provided with outwardly extending blade portions 4 adapted to engage the contacts of a fuse block, not shown, in the well known manner.

In the preferred construction illustrated 80 in the drawings, one of the terminal members 2 is provided with an annular flange 6 arranged to seat upon one end of the casing 1 and to be secured in sealing relation thereto by means of a collar 7 threaded onto said end 85 whereby the terminal may be readily removed and replaced as desired. The other terminal member is provided with a flange 5 which is movable through the casing 1.

A sealing plate 8 is arranged to seat upon 90 the opposite end of the casing 1. The plate 8 is provided with an annular shoulder 9 arranged to fit within the end of the casing. A slot 11 is formed in the plate 8 to receive the blade portion 4 of the adjacent terminal 95 member 2. The plate 8 is also provided with an outwardly extending bearing portion 12 formed concentrically with the plate 8. Lugs 13 are formed upon the edges of the plate 8 and the annular flange portion 6 to engage 100

notches cut into the ends of the casing 1 whereby said plate and flange may be accurately alined in relation to the casing and to each other.

- 5 A clamping member 14 is rotatably mounted upon the bearing portion 12 of the plate 8. The clamping member 14 consists of an annular ring having its inner circumference forming a neat bearing fit upon the bearing 12 and having its outer circumference matching with the circumference of the plate 8. Notches 16 are formed to match with the ends of the slot 11 of the plate 8 and clamping surfaces 17 are inclined in opposite directions from said notches as best shown in 10 Figs. 4 and 5 of the drawings, said surfaces being arranged concentrically with the member 14 and the plate 8, along the inner circumference of the ring.
- 15 The member 14 is preferably secured to the plate 8 so that the two members may be held in assembled relation. This is preferably accomplished by means of a pin 18 secured to the plate 8 and extending outwardly 20 therefrom through an arcuate slot 19 formed in the clamping ring 14. The pin 18 is provided with a head 20 adapted to retain the ring 14 and said pin is made sufficiently long to permit the ring 14 to be 25 moved outwardly thereon sufficiently to clear the bearing portion 12 whereby said ring may be swung to a position such as indicated in dotted lines in Fig. 5 to permit the contacting surfaces of the ring 14 and plate 8 to be 30 inspected and cleaned.

35 In operation, a fusible element 3 is secured between the terminal members 2 by suitable detachable securing members 21 and inserted through the casing so that the flange 6 will seat upon the adjacent end of the casing, the adjacent collar 7 being then applied to secure said flange in sealing relation to the casing. The plate 8 is then moved onto the opposite end of the casing, the blade 4 of the 40 terminal being received within the slot 11 so that the plate may seat against the flange 5 and upon the end of the casing 1. In order to apply the plate 8 it is necessary for the clamping ring to be moved to cause the 45 notches 16 to match with the ends of the slot 11 as shown in Fig. 5 of the drawings. When the plate 8 has been seated, the clamping ring 14 is turned to the right to cause the inclined clamping surfaces 17 to enter notches 22 50 formed in the edges of the blade 4. The ring 14 is rotatable upon the bearing portion 12 of the plate 8 and is held in concentric relation to the plate and to the casing by said bearing. As the ring is turned, the clamping surfaces press the plate 8 firmly against the flange 5 of the terminal 2, thereby effectually 55 clamping said plate and terminal together. A collar 7 is then threaded onto the end of the casing 1, said collar being arranged to 60 press the ring 14 and the plate 8 into sealing

relation to the end of the casing. The slot 19 limits the movement of the ring from a normal applying position with the notches 16 registering with the slot 11 to a full clamping position when moved through approximately 90°.

70 To replace a blown fusible element 3, the collars 7 are removed and the terminal members withdrawn from the casing. A new fusible element 3 is then secured between the terminals and the fuse again assembled as above explained. In replacing a fuse, the plate 8 and clamping ring 14 are normally held assembled together and in proper alinement so that said members cannot be reassembled incorrectly. Furthermore, the bearing portion 12 prevents the ring 14 from getting out of alinement and facilitates the turning of the ring to clamp the parts together without disturbing said alinement. The 75 elongated pin 18 permits the ring 14 to be moved out of engagement with the bearing portion 12 whereby the contacting surfaces between the ring and plate may be cleaned to facilitate the operation of the device when 80 necessary.

85 Having thus described my invention, what I claim as new and desire to secure by Letters Patent is—

- 90 1. The combination with a casing and terminal member of an electric fuse, of a plate adapted to seat upon an end of the casing and slotted to receive the terminal member; a clamping member mounted adjacent the outer face of the plate and provided with inclined surfaces movable to engage notches formed in the terminal member to clamp the plate and terminal member together; and means for centering the clamping member relative to the plate and terminal member.
- 95 100 105 2. The combination with a casing and terminal member of an electric fuse, of a plate adapted to seat upon an end of the casing and slotted to receive the terminal member; a clamping member mounted adjacent the outer face of the plate and provided with inclined surfaces movable to engage notches formed in the terminal member to clamp the plate and terminal members together; and means formed upon the plate for centering the clamping member and forming a bearing rotatably engaging the clamping member.
- 110 115 120 125 130 3. The combination with a casing and terminal member of an electric fuse, of a plate adapted to seat upon an end of the casing and slotted to receive the terminal member; a clamping member mounted adjacent the outer face of the plate and provided with inclined surfaces movable to engage notches formed in the terminal member to clamp the plate and terminal members together; and an outwardly disposed concentric bearing formed upon the plate and rotatably engaging the clamping member for centering said clamping mem-

ber relative to the plate and the terminal member.

4. The combination with a casing and terminal member of an electric fuse, of a plate adapted to seat upon an end of the casing and slotted to receive the terminal member; a clamping member mounted adjacent the outer face of the plate and provided with inclined surfaces movable to engage notches formed in the terminal member to clamp the plate and terminal members together; an outwardly disposed concentric bearing formed upon the plate and rotatably engaging the clamping member for centering said clamping member relative to the plate.
5. The combination with a casing and terminal member of an electric fuse, of a plate adapted to seat upon the end of the casing and slotted to receive the terminal member; a clamping member mounted adjacent the outer face of the plate and movable to engage notches formed in the terminal member to clamp the plate and terminal members together; an outwardly disposed concentric bearing formed upon the plate and rotatably engaging the clamping member for centering said clamping member relative to the plate and terminal member; and a pin secured to the plate and extending outwardly through an arcuate slot formed in the clamping member to limit the movement of said clamping member and to retain said clamping member in assembled relation to the plate.

6. The combination with a casing and terminal member of an electric fuse, of a plate adapted to seat upon the end of the casing and slotted to receive the terminal member; a clamping member mounted adjacent the outer face of the plate and movable to engage notches formed in the terminal member to clamp the plate and terminal members together; an outwardly disposed concentric bearing formed upon the plate and rotatably engaging the clamping member for centering said clamping member relative to the plate and terminal member; a pin secured to the plate and extending outwardly through an arcuate slot formed in the clamping member to limit the movement of said clamping member and to retain said clamping member in assembled relation to the plate, said pin being extended outwardly to permit the clamping member to be moved outwardly out of engagement with the bearing portion and swung away from the face of the plate whereby the contacting surfaces between the plate and clamping member may be cleaned.

7. The combination with a casing and a terminal member of an electric fuse, said terminal member being provided with an outwardly extending blade portion having op-

positely disposed notches formed in the edges thereof, of a plate adapted to seat upon the end of the casing to seal the same, said plate being slotted to receive the terminal blade portion; an outwardly disposed bearing portion formed upon the outer face of the plate concentrically with the plate; a clamping ring rotatably mounted upon the bearing portion and adapted to seat upon outer face of the plate, said ring having notches matching with the ends of the plate slot to receive the edges of the blade portion; and inclined clamping surfaces formed upon the ring and adapted to be moved into the notches of the blade portion to clamp the terminal and plate together.

8. The combination with a casing and a terminal member of an electric fuse, said terminal member being provided with an outwardly extending blade portion having oppositely disposed notches formed in the edges thereof, of a plate adapted to seat upon the end of the casing to seal the same, said plate being slotted to receive the terminal blade portion; an outwardly disposed bearing portion formed upon the outer face of the plate concentrically with the plate; a clamping ring rotatably mounted upon the bearing portion and adapted to seat upon the outer face of the plate, said ring having notches matching with the ends of the plate slot to receive the edges of the blade portion; inclined clamping surfaces formed upon the ring and adapted to be moved into the notches of the blade portion to clamp the terminal and plate together; and means for limiting the rotative movement of the clamping ring relative to the plate.

9. The combination with a casing and a terminal member of an electric fuse, said terminal member being provided with an outwardly extending blade portion having oppositely disposed notches formed in the edges thereof, of a plate adapted to seat upon the end of the casing to seal the same, said plate being slotted to receive the terminal blade portion; an outwardly disposed bearing portion formed upon the outer face of the plate concentrically with the plate; a clamping ring rotatably mounted upon the bearing portion and adapted to seat upon the outer face of the plate, said ring having notches matching with the ends of the plate slot to receive the edges of the blade portion; inclined clamping surfaces formed upon the ring and adapted to be moved into the notches of the blade portion to clamp the terminal and plate together; and means securing the clamping ring upon the plate and adapted to limit the rotative movement of said ring relative to said plate.

10. The combination with a casing and a terminal member of an electric fuse, said terminal member being provided with an

outwardly extending blade portion having oppositely disposed notches formed in the edges thereof; of a plate adapted to seat upon the end of the casing to seal the same, said 5 plate being slotted to receive the terminal blade portion; an outwardly disposed bearing portion formed upon the outer face of the plate concentrically with the plate; a clamping ring rotatably mounted upon the bearing 10 portion and adapted to seat upon the outer face of the plate, said ring having notches matching with the ends of the plate slot to receive the edges of the blade portion; inclined clamping surfaces formed upon the ring and adapted to be moved into the notches of the blade portion to clamp the terminal and plate together; and a pin secured to the plate and extending outwardly through an arcuate slot formed in the ring, said pin and slot being 15 adapted to normally hold the ring and plate in assembled relation and to limit the rotative movement of said ring relative to said plate, said pin being also adapted to permit the ring to be moved out of engagement with the bearing portion and swung away from the face 20 of the plate.

In witness whereof, I hereunto set my signature.

JOHN H. HICKEY.
